(57) **CLAIM**

The ornamental design for a lighting fixture, as shown and described.

DESCRIPTION

FIG. 1 is a top perspective view of a new lighting fixture design;

FIG. 2 is a back elevation view thereof;

FIG. 3 is a left side elevation view thereof;

FIG. 4 is a right side elevation view thereof;

FIG. 5 is a front elevation view thereof;

FIG. 6 is a top plan view thereof; and,

FIG. 7 is a bottom plan view thereof.

The broken lines showing a support stem, mount and mounting surface depict environmental structure that forms no part of the claimed design. The dot-dash-dot line defines the bounds of the claimed design and forms no part thereof.
